UNITED STATES PATENT OFFICE.

WILLIAM B. PALMER, OF HIGHWOOD, ILLINOIS.

NAIL PACKAGE.

Application filed July 29, 1926. Serial No. 125,784.

Workmen, artisans and others engaged in an occupation, such as lathing, shingling, or the like, requiring the free use of nails or analogous fastenings, generally resort to the 5 common practice of holding a quantity of the nails in the mouth for ready and convenient access.

This practice is objectionable, because of the liability of one or more nails lodging in 10 the mouth or throat, or passing into the stomach, and because of contact of the metal with the teeth, lips and tongue, and because unsanitary and the frequent requirement for replenishing the supply.

15 In accordance with this invention a number of nails are formed into a package of a size to be conveniently held in the mouth, said package including a wrapper to retain the nails in place and prevent direct contact 20 thereof with the teeth, lips or tongue.

The invention further contemplates an elastic binder which contracts as the package dwindles by use of the nails, said binder 25 also serving as cushioning means for the teeth to bite into and retain the package in the mouth. The binder may likewise constitute the wrapper and retains the nails in compact form and prevents casual detachment and separation thereof.

30 While the drawings illustrate a preferred embodiment of the invention, it is to be understood that in adapting the means to meet specific needs and requirements the design may be varied and such other changes in 35 the minor details of construction may be resorted to within the scope of the invention as claimed, without departing from the spirit thereof.

For a full understanding of the invention 40 and the merits thereof reference is to be had to the following description and the drawings hereto attached, in which—.

Figure 1 is a side view illustrative of an 45 embodiment of the invention and its manner of use.

Figure 2 is a side view of a nail package embodying the invention, a portion of the 50 wrapper and binder being broken away, and the dotted lines indicating the teeth between which the package is held, and

Figure 3 is a view similar to Figure 2, of a modification.

Corresponding and like parts are referred to in the following description and desig-

nated in the several views of the drawings 55 by like reference characters.

The numeral 1 designates a plurality of nails, or analogous fastenings arranged to 60 to provide a package, the nails being reversely disposed so that the heads of a certain number face in one direction and the heads of a like number face in the opposite direction, and as a result, the package presents an approximate uniform appearance at 65 either end, and is of uniform diameter throughout. The bodies of the nails lie close together and because of the size of the heads the latter occupy different relative positions, and this is of advantage as it enables the 70 nails to be readily and conveniently grasped by the heads when withdrawn from the package for use. The number of nails to a package will vary and depend largely upon the size of the nails, it being 75 observed, however, that the package is of 80 convenient size to be held in the mouth. A wrapper 2 encompasses the nails of a package and may be of any suitable material, paper being preferred, and rendered moisture proof so as not to be affected by the moisture of the mouth when the package is held therein substantially as shown in Figure 1 of the accompanying drawings. A binder 3 is preferably employed to 85 retain the parts in place and this binder is elastic and contracts as the diameter of the package grows smaller as the nails are used. The binder also results in the provision of a cushion for the teeth to bite into, as indicated most clearly in Figures 1 and 2. 90 The binder may consist of a narrow elastic band of rubber which is passed about the package a number of times, as indicated most clearly in Figure 2. The elastic binder occupies a central position so that either end 95 of the package may be held in the mouth.

In the modification shown in Figure 3 the part 4 functions both as a wrapper and binder and consists of a broad band of 100 rubber.

In practice the workman provides himself with a plurality of packages which, for convenience, are placed in a pocket, or other usual holder, one of which is held in the mouth at a time, and when the nails facing in one direction are used the package is reversed so that the heads previously facing inward may be presented outward to be 105

conveniently grasped as the nails are required for use. The wrapper and binder contracting keep the nails in compact form and prevent their separation and casual detachment, as will be readily appreciated.

Having thus described the invention, I claim:

1. A package of nails to be held in the mouth, comprising a number of nails grouped in compact form, and free from any interspacing and separating means, and a contractible binder confining and maintaining

the nails in frictional contact as the package dwindles by withdrawal of the nails therefrom.

2. A nail package to be held in the mouth, comprising nails reversely disposed and grouped to maintain a frictional contact free from separating means, and an elastic maintaining the nails in package form and providing a cushion for the teeth to bite into when the package is held in the mouth.

In testimony whereof I affix my signature.

WILLIAM B. PALMER. [L.S.]
